Specification for Design.

Patented Aug. 26, 1919.

Application filed April 22, 1919. Serial No. 291,991. Term of patent 14 years.

To all whom it may concern:

Be it known that I, MAX LITMAN, a citizen of the United States of America, residing at Springfield, in the county of Hampden and Commonwealth of Massachusetts, have invented a certain new, original, and ornamental Design for a Radiator-Core, of which the following is a specification, reference being had to the accompanying drawing, forming part thereof.

Figure 1 is an elevational view of the radiator, and Fig. 2 is a vertical sectional view of Fig. 1 on an enlarged scale showing my new design.

I claim:

The ornamental design for a radiator core, as shown.

MAX LITMAN.
